UNITED STATES PATENT OFFICE.

CHARLES J. BROWN, OF TONAWANDA, NEW YORK, ASSIGNOR OF ONE-HALF TO LOUIS C. NEWMAN, OF BUFFALO, NEW YORK.

PULP-PRODUCING APPARATUS.

1,380,524.

Specification of Letters Patent.

Patented June 7, 1921.

Application filed July 5, 1918. Serial No. 243,394.

To all whom it may concern:

Be it known that I, CHARLES J. BROWN, a citizen of the United States of America, and a resident of the city of Tonawanda, in 5 the county of Erie and State of New York, have invented certain new and useful Improvements in Pulp-Producing Apparatus, of which the following is a full, clear, and exact description.

10 The principal object of my invention is to provide an apparatus in which the fine pulp shall be continuously taken from the apparatus, when it is of the proper mesh, without in any way interrupting the flow of the 15 coarser pulp, whereby the apparatus is continuous in its operation.

Another object is to provide a screen for separating the fine and coarse pulp which shall be self-cleaning.

20 Another object is to provide a simple and efficient means for discharging the fine pulp from the finishing tub without interrupting the continuous operation of the apparatus.

Moreover, in my invention, I provide a 25 self-cleaning, rotary screen for removing a portion of the fine pulp from either of the tubs.

The above objects and advantages have been accomplished by the device shown in 30 the accompanying drawings, of which:

Figure 1 is a plan view of my apparatus.

Fig. 2 is a longitudinal, sectional view of 35 one of the beater tubs, taken on line 2—2 of Fig. 1.

Fig. 3 is a longitudinal, sectional view of the finishing beater tub, taken on line 3—3 of Fig. 1.

40 Fig. 4 is a longitudinal, fragmentary, sectional view of the finishing tub, showing a rotary screen arranged in the discharge trough.

Fig. 5 shows a modified arrangement of my apparatus.

45 Fig. 6 is an enlarged, fragmentary, sectional view of a gate valve to be used in connection with the form of apparatus shown in Fig. 5.

Fig. 7 is a similar view of a modified form 50 of gate valve.

Fig. 8 is an enlarged, sectional view of a modified form of backfall.

55 Fig. 9 is a fragmentary, plan view of a beater engine, showing my rotary screen attached thereto.

Fig. 10 is an enlarged, transverse, sectional view of the same, taken on line 10—10 of Fig. 9.

Fig. 11 is an enlarged, fragmentary, longitudinal, sectional view, taken through the 60 tub on line 11—11 of Fig. 9, showing the rotary screen and its co-acting parts.

Referring to Figs. 1 to 3 of the drawings, it will be seen that my apparatus comprises preferably three beating tubs, 15, 16, and 17. The tub 15 is the roughing tub, in which the material to be treated is first placed; and this tub is connected with the middle tub 16, by means of a channel 18. From the middle tub 16, the material is conducted to the finishing tub 17, through a channel 19. The channel 18 and the side of the middle tub 16, nearest the connection to the channel, are each preferably provided with the usual sand and metal catchers 20, 70 which are preferably in the form of lateral strips, secured to the bottom of the channel and tub, as shown. If desired, heating pipes 20^a may be arranged along the sides of the channel and tub, preferably near the bottom thereof, and adjacent the metal catchers 20, for assisting in the separation of the metal and sand from the pulp. In this form of the apparatus, the tubs are arranged at different elevations. The tub 15 is the highest, the middle tub 16 is arranged lower than the tub 15, and the tub 17 is the lowest of the three, so that the material will flow from one tub to the other by gravity. 80

Each of the tubs comprises, in general, an 90 outer wall 21; a midfeather 22; a beating roll 23, provided with blades 24; a bed-plate 25, co-acting with the beater roll; and a backfall 26, all of the usual and well known construction. The outer wall 21, at 95 the end of each of the tubs, is cut away so as to provide openings 27, 28, and 29 in the tubs 15, 16, and 17, respectively, such openings extending from the top to the bottom of each tub. The opening 27 of the tub 15 and 100 the opening 28 of the tub 16, are each arranged in the end of the tub and immediately behind the backfall 26 of each tub; and, arranged in front of each of these openings, is a comblike or open ended screen 30. 105 These screens, as shown in Fig. 2, are composed of a plurality of bars or members closely arranged parallel to each other and secured at their inner ends at a point 30^a to the side of the tub of the engine, at one end 110

only the other ends being unattached. The point 30^a is disposed at the side of the tub and toward the direction of flow of the material. The outer ends of the members of 5 the screen are free, not being fastened together and the spaces between them are open. Each screen is preferably curved and is secured in front of the opening, as shown in the drawings. The flow of the material 10 is as illustrated by the arrows, and, as the current forces the material past and in contact with the screen, the particles which are fine enough to pass between its members will flow into the channels connected with the 15 opening immediately behind the screen, while the coarser and unfinished stock will move over the surface of the screen and continue to circulate through the beater until it has become fine enough to pass through 20 the screen. The screen of the tub 15 is coarser in mesh than the screen of the tub 16; and, by this arrangement, the pulp which is but partially reduced in the first tub passes to the middle tub where the 25 reducing process is continued, and then on to the third or finishing tub where the pulp is reduced to the predetermined fineness.

The finishing tub 17 is not provided with a screen 30, but the pulp is recirculated until 30 it becomes of the proper fineness, when it is removed therefrom. A hood 31 is arranged over the beating roll of this tub (not shown in Fig. 1), and the part thereof which is adjacent the backfall is curved to conform 35 to the shape of the roll, being arranged but a slight distance above the roll. To the end 32 of this hood is pivotally secured an adjustable baffle valve 33. This valve is arranged so that the space between the end 40 32 of the hood and the top edge of the backfall 26 may be closed. A lever 34 and suitable connecting means are provided, whereby by this valve may be operated to wholly or partially close the space between the edge 32 45 of the hood and the top of the backfall. Under normal working conditions, the lower edge of the valve is disposed near the periphery of the roll, as shown by the full lines in Fig. 3. When it is desired to empty the 50 tub, the valve is moved back to the position shown in dotted lines, where the opening between the backfall and hood is closed. In this position, the material will be conducted around over the top of the roll and under the 55 hood 31. In front of the roll is arranged a screen 35 through which the fine material passes as it is thrown against it by the roll. Immediately in front of the roll is disposed a discharge trough 36; and to the upper 60 edge of the inner wall thereof is pivotally mounted a valve 37, which may be moved, by suitable means (not shown), toward or from the lower end of the screen 35. A baffle plate 38 is arranged in front of the 65 screen for preventing the material from be-

ing thrown beyond this point. With the valve 37 properly adjusted, the fine material, passing through the screen, will fall into the discharge trough 36, whence it will be conducted to the discharge pipe 39. The 70 baffle valve 33 is preferably so adjusted that there is a continuous flow of material through the screen 35 which is produced by the roll 23, a portion of the stock in the beating tub passing over the backfall and re-circulating through the tub. Both the baffle valve 33 and the valve 37 may be adjusted so as to graduate the discharge of the material from the finishing tub 17, and they are, 75 preferably, so adjusted that there is a continuous flow of material from the tub. 80

Instead of the trough 36, shown in Fig. 3, a trough 40 having a circular cross section may be used. When such a trough (as shown in Fig. 4) is used, a cylindrical screen 85 41, rotated by suitable means (not shown), is arranged so as to dip into the trough. This screen is hollow and is provided with a plurality of perforations through its wall. When rotated in the material, the product 90 which is sufficiently fine will pass through the openings and be conducted away. The coarser materials, which will stick to the outside of the screen, will be scraped off by means of a doctor 42 and conducted back 95 to the beating tub through a slot 43 in the hood.

Referring to Fig. 5, where I show a two-stage apparatus, 44 and 45 are roughing tubs into which the scrap paper is first 100 placed. These tubs are connected with a finishing tub 46 by means of channels 47 and 48, respectively. 49 is the screen which is arranged in front of the opening in each of the tubs 44 and 45. Sand and metal 105 catchers 20 are arranged in the tubs 44 and 45, and also in the channels 47 and 48. In this form of invention, the tubs 44 and 45 are both arranged at the same elevation but are higher than the elevation of the finishing tub 46. In each of the channels 47 and 48 is arranged a gate valve 50, by which either of the channels may be closed. This gate valve may be in any desired form, and, 110 in the drawings, in Figs. 6 and 7, I show 115 two forms. In Fig. 6, the valve 50 is arranged so as to slide vertically in the channel, and it is provided with a gear rack 51, meshing with a gear pinion 52, by which, through suitable operating means (not 120 shown), it may be raised or lowered as desired. In Fig. 7, the gate valve 53 is double-sided and pivoted at its center to a shaft 54. The shaft is supported in suitable bearings and is rotatable in the direction indicated by the arrows by any suitable means (not shown). By means of these gate valves, either of the tubs 44 or 45 may be used while the other is being charged; or, if the condition of the material warrants, both tubs 44 125 130

and 45 may be used to supply the partly treated stock to the finishing tub 46.

In Fig. 8, I show an adjustable backfall 55, which is slidably arranged in suitable ways upon the bottom 56 of the tub. This backfall is provided with a gear rack 57, and the gear pinion 58 meshes therewith. The pinion 58 is secured to a shaft 59 which may be rotated by a lever 60. Upon the 10 surface of the backfall, adjacent the beater roll 61, is arranged a beating surface 62 which co-acts with the blades of the beating roll. By operating the lever 60, the beating surface 62 may be moved toward or 15 away from the blades of the beating roll, thereby regulating the grade of stock.

In Figs. 9 to 11, inclusive, I show an alternate method of removing the fine stock from the finishing beating tub. A rotary 20 screen 63 is arranged near the bottom of the beating tub. It is suitably journaled and driven by means of a gear 64, attached to the screen, and an intermeshing gear 65 carried by a jack-shaft 66. The jack-shaft 25 is driven preferably from the main shaft 67 of the beating tub, by means of pulleys 68 and 69 and belt 70. The rotary screen 63 is provided with a plurality of perforations of such a size that the material which 30 has reached the proper fineness will pass therethrough. The outer end of the screen is rotatably arranged in an overflow or head box 71. This head box is provided with a vertical partition 72, the height of which is 35 adjustable by means of blocks 73. This partition thus provides a discharge pipe 74 for the finished material. The blocks 73 provide means for adjusting the partition so that its height will be about level with 40 the material in the tub. The fine material passes through the apertures in the rotary screen and into the head box. It rises in the head box until it overflows the partition and passes thence into the discharge pipe 45 74. Arranged immediately in front of the rotary screen 63 is a stationary screen 75 which slopes upwardly in the direction of flow of the material and thus serves to conduct the heavier material over the top of 50 the rotary screen 63, while the finer material passes between its members and through the apertures of the rotary screen. The lower end of the screen 65 is supported by means of a lateral strip 76 which provides a 55 sand and metal catch. A settling basin 77 is provided below the rotary screen 63. A doctor 78 is provided for the rotary screen 63, whereby its periphery is kept clear of the coarse material.

60 It will be seen that by the means of my apparatus, scrap paper may be continuously charged into the roughing beating tubs and that the material, as it is made finer, will automatically pass on to the next succeeding tub and so on until it reaches the finished

tub, where the material of proper fineness will be continuously conducted away.

I prefer to provide a rotary screen in the finishing tub only, but it is clear that one may be provided in either of the tubs for 70 taking off any fine material which might be present. This makes it unnecessary for the material in any one tub, which has become of the proper fineness, to pass through the other tubs, but makes it possible to conduct 75 the fine material directly from either of the tubs. The beating tubs may either be arranged in series or in alternate arrangement, as desired. These and other modifications of the details herein shown and described 80 may be made without departing from the spirit of my invention or the scope of the appended claims; and I do not, therefore, wish to be limited to the exact embodiment herein shown and described.

Having thus described my invention, what I claim is:

1. In a pulp producing apparatus, the combination of a plurality of beating tubs, channels connecting the tubs, each tub having its 90 wall cut away at the point where it connects with one of the channels, and a screen arranged across the opening connecting the tub with the channel.

2. In a pulp producing apparatus, the combination of a plurality of beating tubs, channels connecting the tubs, each tub having its wall cut away the full height of the tub at the point where it connects with one of the channels, and a screen arranged across the 100 opening connecting the tub with the channel.

3. In a pulp producing apparatus, the combination with a beating tub, having its wall cut away the full height of the tub, of a comb like, open-ended screen arranged 105 across the opening of the tub.

4. In a pulp producing apparatus, the combination of a plurality of beating tubs, channels connecting the tubs, each tub having its 110 wall cut away at the point where it connects with one of the channels, and comb like, open-ended screen arranged across the opening connecting the tub with the channel.

5. In a pulp producing apparatus, the combination with a beating tub, having its 115 wall cut away the full height of the tub, of a curved, comb like open-ended screen arranged across the opening of the tub and so positioned that the fine pulp will pass through the meshes of the screen and the 120 coarse pulp will be retained in the tub for further reduction.

6. In a pulp producing apparatus, the combination with a plurality of beating tubs, channels connecting the tubs, each tub having its wall cut away at the point where it connects with one of the channels, each tub having a beating roll and a backfall, the last tub having a baffle valve pivotally supported above the backfall, means for ad- 130

justing the baffle valve, a discharge trough for collecting the fine material carried over by the roll, and a pivotally mounted valve arranged between the trough and the comb-like screen for directing the flow of the pulp to the trough.

7. In a pulp producing apparatus, the combination with a plurality of beating tubs, channels connecting the tubs, each tub having its wall cut away at the point where it connects with one of the channels, a screen arranged across the opening connecting the

tub with the channel, each tub having a beating roll and a backfall, the last tub having a baffle valve pivotally supported above the backfall, means for adjusting the baffle valve, a discharge trough for collecting the fine material carried over by the roll, and a pivotally mounted valve arranged between the trough and the comb-like screen for directing the flow of the pulp to the trough.

In testimony whereof I have hereunto signed my name.

CHARLES J. BROWN.
